UNITED STATES PATENT OFFICE.

CLARK ECKERT, OF LOSANTVILLE, INDIANA.

DESIGN FOR AN INSOLE.

SPECIFICATION forming part of Design No. 26,306, dated November 17, 1896.

Application filed July 14, 1896. Serial No. 599,191. Term of patent 14 years.

To all whom it may concern:

Be it known that I, CLARK ECKERT, a citizen of the United States, residing at Losantville, in the county of Randolph and State of Indiana, have invented and produced a certain new and original Design for Spring-Insoles for Boots and Shoes; and I do declare the following to be a full, clear, and exact description of the invention, such as will enable others skilled in the art to which it applies to make and use the same.

My invention relates to a new and useful design for insoles for boots and shoes; and it consists of a design of the configuration and ornamentation shown in the accompanying drawings, in which—

Figure 1 is a perspective view of my new design, and Fig. 2 is a transverse sectional view of the same.

The leading feature of my design is an insole convex from side to side throughout its entire length and having bulges *a*, *b*, and *c* and perforations *e*.

What I claim is—

The design for an insole for boots and shoes, as herein shown and described.

In testimony whereof I hereunto affix my signature in presence of two witnesses.

CLARK ECKERT.
